ARTICLE-POSITIONING MEANS FOR LABELING MACHINES.

Application filed March 20, 1926. Serial No. 26,270.

- This invention is an article positioning means designed for use, more particularly, in conjunction with a labeling machine, although said invention may be adapted for 5 machines other than labeling machines to meet such conditions as require articles to be presented in a predetermined relation to mechanism operating to perform useful work on such articles.
- 10 It is a common practice in packaging various commodities to utilize containers, such as bottles or jars, provided or embellished with integral matter of an identifying or advertising character, such as the brand of 15 the commodity, or the name and address of the packer, which are blown into the glass or embossed in the metal composing the container, such identifying or advertising matter occupying a portion of the surface of 20 said container, leaving a definite part of such surface exposed for the reception of a label, the latter being adhesively applied to the exposed free surface. Obviously, it is not desirable to affix labels to the containers 25 in a manner to lap over or conceal the identifying matter, in whole or in part, but so far as I am aware, no provision has heretofore been made in machines for affixing labels by which a succession of containers of 30 the character described are or may be presented each in a predetermined position with respect to labeling mechanism, whereby labels are applied with precision to successive articles and in a manner to cover the exposed 35 or free surface of each article without lapsing over or covering, in whole or in part, that surface of said article embellished with said identifying or advertising subject-matter.
- 40 My invention embodies mechanism for presenting articles in a predetermined position with respect to a labeling mechanism, said presenting mechanism including an appropriate article feeding means, together 45 with article contacting means in movable relation to said article feeding means. The article contacting means is essentially movable with respect to the article feeding means and is co-operative with the more or 50 less protuberant surface produced upon the article by the presence of the identifying or advertising matter thereon, said article contacting means acting to impart rotative movement to the article while in transit due 55 to the operation of the article feeding means, and which rotative movement has the effect

of bodily turning each of the successive articles with respect to the article feeding means in a manner to ultimately present the label receiving surfaces of the successive articles into the required relation to the labeling mechanism for the reception of labels from said mechanism.

In a practical embodiment of the article contacting means, provision is made, first, 60 for the use of rotary members which are positively driven and are positioned for frictional contact with the surfaces of the articles as and when advanced by the feeding means; second, said rotary members are 65 preferably, though not essentially, brushes with relatively stiff flexible bristles which I have ascertained by experience have the capacity of imparting rotative motive to the 70 articles; and, third, the desired rotative movement is given to each article at successive stages or periods by the co-operation 75 with the articles of a plurality of rotary brush devices, and of appropriate pusher devices.

In my invention, a plurality of pusher devices are associated with the rotary brush devices to effect the introduction of the articles successively, and to displace one article by pushing another article against the one to be displaced, there being periods of 80 rest in the feed motion given to the articles in the operations of moving said articles ultimately to one of a plurality of carriers, upon one of which carriers the articles are 85 deposited in positions for presentation to the labeling mechanism.

It is preferred to employ a plurality of carriers, usually in the form of aprons, one for moving the articles to the first pusher device, and the other for conveying the articles from the rotary brushes and the second pusher device and for presenting said articles to the labeling mechanism. The first carrier is usually operated with a continuous motion, whereas the second carrier is operated with an intermittent motion, said second carrier being timed in its action 90 with the operation of the pusher devices.

Cooperating with the pusher device is a 95 stopping mechanism, preferably embodied in the form of an escapement adapted to be interposed in the path of articles and positioned intermediate the stations at which the articles are subjected to the action of the 100 plurality of rotary brushes, the function of said stopping device or escapement being to 105

arrest the premature movement of an article from the first station toward the second station, and to thus act as a mechanical barrier to the articles during the period of operation of the brushes upon an article at the second station.

The brush at the first station acts upon the article to preliminarily position said article for action by the brushes of the second station, the escapement being in operative position to arrest the feed movement of the article.

The second station includes a plurality of rotary brushes rotatable in opposite directions to each other, and positioned at one side of the path of movement of the articles, and the pusher device at the second station is operable for bodily moving each article out of the line of feed and so as to carry each article to and from a position intermediate the oppositely rotatable brushes, whereby the article is subjected to the frictional contact of said brushes for the purpose of turning said article into a position wherein the embellished surface is away from the labeling mechanism, whereas the smooth surface reserved for the label is in facing relation to said labeling mechanism.

Other functions and advantages of the invention will appear from the following description taken in connection with the drawings, wherein—

Figure 1 is a plan view of my article positioning mechanism associated with an appropriate label-affixing mechanism and illustrating articles in position upon the initial carrier, the feeding carrier, and at the two stations so as to be subjected to the action of the rotary brushing devices.

Figure 2 is a plan view of the article positioning means illustrating the second pusher slide in position ready to deliver an article to the second carrier after said article shall have been rotated to the required position by the brushes at the second station.

Figure 3 is a plan view of the mechanism shown in Figures 1 and 2, but showing the article in position to be moved by the second pusher device out of the line of feed in order to introduce the article into the second station and between the oppositely rotating brushes, the escapement being lowered into the path of an article at the first station so as to detain said article at said first station.

Figure 4 is a horizontal sectional view in the plane of the dotted line 4—4 of Figure 7, the plane of the section being below the pusher devices and the brush devices and illustrating the driving means for the cam shaft, the carriers, and the brush devices.

Figure 5 is a sectional elevation in the plane of the dotted line 5—5 of Figure 2, illustrating the escapement and the second pusher device by which the article is carried to the second station.

Figure 6 is a detail vertical section illustrating the relation of the second carrier to the table and to the articles when the latter shall have been rotated to the positions required for presentation to the labeling mechanism.

Figure 7 is a vertical section in the plane of the dotted line 7—7 of Figure 1.

Figure 8 is a detail section in the plane of the dotted line 8—8 of Figure 1.

Figure 9 is a detail sectional elevation of the means by which intermittent feed motion is given to the second carrier, the plane of the section being indicated by the dotted line 9—9 of Figures 1 and 4.

Figures 10 and 11 are detail views of parts to be hereinafter described.

As shown in the drawings, a carrier A is employed for feeding articles Y into the path of a pusher device B, the latter being movable across said carrier at the inner delivery portion thereof. The carrier is shown as an endless apron extending a desired distance away from a table C so as to expose said carrier for easy access by an attendant in order to supply the articles to the carrier as rapidly as required, but obviously the supply of the articles may be effected by mechanical contrivances (not shown). Said carrier runs between article guides a fixed to the table, and at the delivery end said carrier is supported by a pulley a', the latter being positioned below the table C, and being mounted on a shaft A' (see Figure 4). Said shaft is connected by a chain and sprocket transmission a² with a drive shaft D, positioned below the table and provided with a power pulley d, or other means for driving said shaft may be resorted to, if desired.

The pusher B is shown as a slide resting upon the table and confined between guides b b', see Figure 8, one of which is provided with a top flange b² which overhangs said slide. The slide is impelled in a direction toward the article Y on the carrier A by a spring B', shown as a coiled spring with one end attached to the slide and the other end anchored on the table. Means are provided for forcibly moving the slide in a direction in opposition to the tension of the spring, said means being timed to periodically actuate the slide in unison with the actions of a second pusher E, a second carrier F, and an article stopping device or escapement G. As shown, the means for moving the pusher slide B is a lever B² fulcrumed intermediate its ends, at b³, said lever being positioned for one end portion to have contact with a stud b⁴ fixed on the pusher slide and provided at its other end portion with a friction roller b⁵, the latter riding against the periphery of a cam B³. Said cam is attached fixedly to a vertically positioned cam shaft H, extending through

table C and journaled in appropriate bearings h , said cam shaft being driven by the shaft D through intermeshing bevel gears h' , h'' , see Figure 7. I designates a rotary brush mounted on a vertical shaft i extending through the table and supported in appropriate bearings below said table. Said rotary brush is positioned adjacent the delivery end of carrier A and to the line of movement of pusher slide B. With said rotary brush co-operates a barrier J, shown as a curved plate fixedly attached to one of the carrier guides a , said barrier plate being in facing relation to the brush, and spaced with respect thereto, the interval separating the brush and the barrier plate being a trifle less than the diameter of article Y, see Figures 1, 2 and 3, whereby the bristles of said brush are adapted to have the required contact with a protuberant surface on the article Y to effect a partial rotation of said article. The brush I and barrier plate J constitute the first station at which the article is stopped in its movement toward the labeling mechanism, and at this period of dwell in the movement of the article toward the labeling mechanism said article is acted upon by brush I for the purpose of having rotative movement given to said article, thus placing said article at the first station in position to be acted upon subsequently (at the second station) in order to place each article in the position for presentation to the labeling mechanism, as will presently appear.

It should be stated that carrier A is operated with a continuous movement, whereas the pusher slide B is operated with an intermittent movement the period of which is determined by the form of cam B^3 . Furthermore, the travel of the pusher slide with respect to the carrier A is limited to the extent of displacing said article from the carrier and to moving it to a position between the rotary brush I and barrier plate J at the first station, but to eject the article from said first station between the brush and the barrier, a subsequent article is required to be moved by the pusher slide against the article occupying the first station, the impact of the following article against the preceding article being sufficient to displace the article from said station, provided the escapement member G is lifted out of the path of said article at said first station. The movement of the pusher slide toward the articles is obtained by the action of spring B' , and is not a positive cam actuated movement, as a result of which the articles are displaced by spring pressure from the carrier and from the first station, whereby breakage of the articles is minimized should the articles become jammed at the first station, for the reason that the spring will not impel the slide, but will permit it

to stop should the first station become clogged, more or less.

The second pusher E is shown as a slide positioned on table C for movement at a right angle to the direction of movement of the first pusher slide B, said second pusher slide E being reciprocable across the path of articles when ejected from the first station, and said pusher slide E being movable to an extent sufficient to carry the article to the second station positioned beyond the line of movement extending normally through the first station and the carrier F. Said pusher slide E is confined for movement in a rectilinear path on table C by appropriate guiding means, herein shown as a depending rib e on the slide fitting in a slot e' of the table (see Figure 7). The inner end portion of said pusher slide E is provided with a metallic member E' which carries a friction roller e^2 , said member E' being chambered at e^3 to receive the free end portion of a spring buffer E^2 (see Figure 10), said buffer being shown as a leaf spring fixedly secured by screws e^4 to the pusher slide. The buffer extends part way across the end portion of the pusher slide, toward the roller e^2 , and it is adapted for contact with an article on the inward travel of the slide E, such contact being a yielding one so that the buffer will be pressed toward or into chamber e^3 should the resistance of the article, in the event of jamming said articles at the second station, be sufficient to bend or deflect the spring, thus minimizing the liability of breakage, or should fragments of a broken article become lodged in the mechanism.

Said second pusher slide, E, is moved in one direction by spring pressure and is positively moved in an opposite direction by cam controlled mechanism, the latter acting to periodically impart movement to said slide and to time such movements with the operation of the escapement G, the second carrier, F, and the first pusher slide B. The movement of the second pusher slide E into contact with the article is by spring pressure, for which purpose I use a spring K, one end of which is attached to the slide and the other end anchored on a fixed part, such as the bridge plate k .

The means for positively actuating the second pusher slide are shown as a vertical rock shaft E^3 , lever arms E^4 , E^5 , and a cam E^6 , and a stud e^6 , see Figures 1, 2, 3, and 7. The stud e^6 depends from the guide rib e of the pusher slide, and with this stud contacts one end of the lever arm E^5 (see Figure 7), the latter being fixed to the lower end of rock shaft E^3 , which rock shaft extends through table C and is journaled in appropriate bearings (not shown). The lever arm E^4 is fixedly secured to the upper portion of the rock shaft, and at its free end

said lever arm is provided with a friction roller e^7 which is presented into frictional contact with the periphery of the cam E^6 , the latter being fixedly attached to the vertical cam shaft H at a point below the cam B^3 by which pusher slide B is actuated, as heretofore described. The rib e on the bottom of the pusher slide E extends inwardly beyond the spring buffer E^2 , such extended portion of the slide-rib e being indicated at e^8 in Figures 1, 2, 3, 5 and 6, and on the end of such extension e^8 of said slide is fixedly secured a contact post E^9 composed of any material suitable for the purpose. Said contact post E^9 extends upwardly from the extension e^8 of said pusher slide E , and passes through the slot e' of table C , said post being in facing relation to the spring buffer E^2 , and being separated from the latter by an interval the width of which is equal, approximately, to the diameter of an article Y . With the slide E in the position of Figure 2, an article ejected from the first station between brush I and barrier J is adapted to be shoved out of the first station and into the space intervening spring buffer E^2 and contact post E^9 of slide E , as shown in Figure 2, and upon the inward movement of the slide, under the tension of spring K , and when permitted by cam E^6 , the article is moved over table C by the slide and its connected parts, buffer E^2 and post E^9 , whereby the article is carried by slide E away from the normal line of article feed (which extends through slide B and carrier F), and said article is thus shifted by said slide E and its contained parts into the second station.

The second station at which the article is permitted to dwell for a brief period is constituted in part by a certain area of table C and in part by a set of co-operating rotary devices herein shown as brushes L , M , the same being adjacent the path of pusher slide E and contiguous to the loading end of second carrier F . Said brushes are supported on brush shafts l , m , for rotation therewith, said brush shafts extending through table C and journaled in appropriate bearings thereon. The brushes L , M , are positively rotated and are driven in opposite directions to each other, said brushes being separated by an interval the width of which is approximately less than the diameter of the article Y , as a result of which the bristles of the complementary set of brushes are adapted for frictional contact with the protuberant surface of the article Y for the purpose of imparting rotative movement to said article while it is at rest temporarily between said brushes, at which time the slide E is at rest while the brushes are rotating. On the outward movement of slide E the article is carried away from the second station and from rotary brushes L , M , by the movement of the

contact post E^9 with said slide, and the article is thus restored to the path of normal feed of the articles extending through pusher slide B and second carrier F , whereby the article after having been subjected to the action of brushes L , M , is brought back into the path of a subsequent article displaced from the first station by the action of pusher slide B in feeding a following (third) article against the article which occupies the first station between brush I and barrier J , it being understood that the movement of the article from the first station toward and against the article after the latter shall have been acted upon by brushes L , M , and restored to the line of feed, results in the displacement of said article, thus restored away from the second pusher slide E and thereby is shoved or impelled upon the loading end of the second carrier F .

The shafts i , l , m , of brushes I , L , M , are provided with pulleys for the reception of suitable belts, as shown in Figure 4. The brush shaft i is driven from cam shaft H by a belt i' , whereas the shafts l , m , are driven by belts l' , m' , from brush shaft i , the belt m' being a crossed belt, so that all the brushes I , L , M , are continuously driven at the speeds required, and brushes L , M , are rotated in opposite direction to each other.

The brushes I , L , M , are of any appropriate form, size and materials, but I have found by experience that a brush with relatively flexible metallic bristles is particularly well adapted for action upon an article a portion of the surface of which is roughened, more or less, by the provision thereon of identification or advertising matter, whereby said brush is adapted to impart to said article a semi-rotative movement.

For moving the articles after treatment at the second station, any means suitable for the purpose may be employed. One such means is shown as the carrier F consisting of an endless apron. Said carrier apron is in operative relation to table C , the loading end of said carrier apron being adjacent the path of the second slide E , and said end being supported by a pulley f carried by a horizontal shaft f' , see Figures 4 and 6. The carrier apron is moved intermittently by appropriate means, and as one means to effect such intermittent motion, I may use the so-called "Geneva movement". The pulley shaft f' is connected by bevel gears f^3 to a divided shaft f^4 , one member of said divided shaft f^4 being provided with a bevel gear f^5 in mesh with bevel gear k^2 of the cam shaft H , see Figure 7. The shaft f^4 is thus driven by the cam shaft, and the two parts of said divided shaft are equipped with members f^2 , f^2 , analogous to the members of the well known "Geneva movement", the same operating in a well understood manner to impart motion intermittently to

the shaft f' for driving the carrier apron with a step motion. This carrier apron F moves the articles along table C and presents said articles in predetermined positions to a labeling mechanism O, one form of which is depicted in Figure 1. It is apparent that any appropriate labeling mechanism may be used; but in the drawings I have illustrated a labeling mechanism 10 wherein the labels are contained in a magazine o that is movable relatively to the path of article feed by a vibratory lever o', substantially as disclosed in a Patent 1,425,351, granted to me on August 8, 1922, for labeling machine.

A stopping device is employed intermediate the first station and the second station for arresting the movement of articles prematurely to the second station, 20 which articles are supplied automatically by continuously acting carrier A and intermittently acting pusher slide B. Said stopping device is shown in Figure 5 as an escapement bar extending alongside the first station, between the brush I and pusher slide E, so that the bar is adapted to be interposed between two articles, one occupying the first station and the other being under the control of pusher slide E. Said 25 escapement bar is hung at g to a lug g' on the table, the free end of said bar being slidable in a keeper g² fixed to the table adjacent the second station. The escapement bar is depressed into the path of an article occupying the first station by a spring G', one end of which is attached to the escapement bar intermediate its ends, whereas the other end of the spring is attached to the bridge member k, see Figure 5. Said 30 escapement bar is provided with a roller shoe g⁴ which is adapted to lie in the path of a cam lug g⁵ provided at a suitable point on the second pusher slide E, said cam lug g⁵ acting to lift the escapement bar out of the path of feed of the article when the slide E is in outward position and to retain said escapement bar in the raised position during that period at which the article is moved away from the first station and into position 45 between the parts E² E⁹ of said pusher slide E. With the pusher slide E at rest in the position of Figures 2 and 5, the escapement bar G is held in a raised position by cam lug g⁵, and thus lifted out of the 50 path of the article to be shoved out of the first station between brush I and barrier J, but as the pusher slide E begins its inward movement, under the impulse of spring K and as determined by the contour of cam E⁶, the cam lug g⁵ moves with the pusher slide E away from roller g⁴, whereupon spring G' depresses the escapement bar G into the path of the article occupying the first station, so that said article cannot be ejected 55 from the first station for that period re-

quired for the second pusher slide to carry an article into the second station, for brushes L M to act upon said article at said second station, and for said pusher slide E to return said article from the second station 70 to a position in alignment with the article at the first station and with the second carrier F, whereupon the cam lug g⁵ again lifts the escapement bar in order that the article when displaced from the first station will 75 push the article resting between posts E² E⁹ of the second slide away from said slide and onto the carrier F. The cam E⁶ by which movement is given to the second pusher slide is of such formation that it not 80 only permits the spring K to move the slide under spring pressure in one direction, but it controls the motion of the second pusher slide in a manner to impart thereto a period of rest or dwell when said slide shall have 85 been moved inwardly to carry an article to the second station, thus actuating the slide E in a manner to carry the article to and from the second station, and to permit the article to rest or dwell for a length of time 90 required for the co-acting brushes L M to impart a semi-rotative movement to said article while it occupies the second station.

The use of the intermittently actuated carrier apron F in conjunction with a labeling mechanism the magazine of which is reciprocable with respect to the path of the article feed, makes it desirable to employ some means for precluding displacement of the article upon the carrier apron by the contact of the movable magazine with said article in directly applying a label from the magazine to the article. For retaining the articles against displacement under such conditions, I have shown a forked retaining member P positioned in line with the magazine o and adapted to partially embrace the article while the latter remains seated upon the carrier apron F. This forked retaining member is carried by a slide p, under the partial control of a spring p', with which forked member co-operates a lever arm q on a rock shaft q', see Figures 1 and 4. Said rock shaft is provided with a lever arm q², to which is linked one end of a rod q³, the other end of which is provided with a friction roller q⁴ positioned in the path of a cam Q fixedly attached to shaft f', see Figures 4 and 11. The rotation of the cam imparts endwise movement intermittently to rod q³ 105 for moving the forked retainer P toward and from the path of articles advanced by the carrier F. With the article moved by the carrier into a position in register with the magazine, as shown in Figure 1, and with the carrier F at rest, the forked retainer is moved by lever arm q into a position to embrace the article, whereupon the magazine o is shifted to apply a label to said article, at which time the retainer precludes 110

displacement of said article from the carrier apron. The magazine moves away from the article, the retainer is withdrawn from contact with said article, and the latter is 5 carried away from the label receiving position by the movement of the apron F.

As hereinbefore stated, my invention is useful in connection with articles of one form or another, usually with articles the 10 surfaces of which are provided with identification or advertising matter, such as with glass containers having a brand or name of the packer blown into the glass, or with metal containers having the brand or pack- 15 er's name embossed in the metal, which blown glass containers or embossed metal containers constitute a characteristic roughness, more or less, upon a portion only of the surface. As indicative of this condition, 20 I have shown each container Y in Figures 1, 2, 3, 5 and 6, as provided with a roughened surface at y, leaving the label receiving surface y' in a relatively smooth condition. Obviously, it is desirable to apply the label 25 to the smooth surface y' only of the container, and without permitting the end portions of said label to overlap the embellished surface y, partially or wholly, but the act of supplying the containers in indiscriminate 30 or irregular fashion to the carrier A requires the mechanism herein disclosed to act automatically in imparting to each container or article a semi-rotative motion, or a succession of semi-rotative movements, in order 35 that the articles when advanced to the second carrier F will each occupy such a position on said carrier that said article will present its label receiving surface y' opposite to or in register with the labeling mechanism O. 40 In the main, the operation of the mechanism will be understood from the preceding description; but it may be summarized as follows, taking one article as an example. It is moved by carrier A into a position in line 45 with pusher slide B, the inward motion of which shoves the article into the first station, between brush I and barrier J. Assuming that the roughened surface y of the article is presented to brush I, the bristles 50 of said rotary brush act frictionally upon said surface y for imparting a semi-rotative movement to the article, but with the smooth surface y' of the article presented to the brush, the article will remain at rest between 55 the barrier and the brush. With the escape- 60 ment bar G raised and the slide E in the position of Figure 2, the next inward movement of slide B pushes a second article against the first article temporarily occupying the first station, the effect of which is to displace the first article away from the station between I, J and to shove it between parts E² E³ of pusher slide E, the second article thus assuming position at the first 65 station. The first article is now carried by

pusher slide E to the second station, the escapement bar G being lowered into the path of the second article at the first station. The inward movement of pusher slide E thus positions the first article between 70 brushes L, M, at which time slide E remains at rest, but the brushes are driven so that the bristles thereof are in frictional contact with the article. With the article Y on slide E in position to present its roughened surface 75 into contact with either brush L M at the second station, said brushes, or one of them, act upon the article to give it a partial turn until such time as the article occupies a position at which the brushes act only upon 80 the smooth surface of the article, the article being turned for the roughened surface y to lie between the circular planes of the brushes, as shown in Figure 1. The article is thus moved by the brushes, individually or 85 jointly, for the smooth surface y' to face in a direction toward the labeling mechanism and for the roughened surface y to face in a direction away from the labeling mechanism. The action of brushes L M on the 90 article while at the second station is effected during the period of rest of the second pusher slide at the limit of its inward movement, but on the outward movement of the slide 95 E, the article is carried away from the second station and restored to a position in line with the article at the first station, so that as the second pusher slide reaches the limit of its outward movement, the cam g⁵ 100 acts to lift the escapement bar G. With the first article thus restored to a position in line with the second article and with the carrier F, after the said article shall have been rotated to the required position for presentation of its label receiving surface to the label magazine, the second article is ejected from the first station by a following (third) 105 article, and this movement of the second article pushes the first article away from the second pusher slide and shoves the said first article upon the second carrier F by which it is ultimately presented in the desired position to the label magazine and to the forked retainer.

Having thus fully described the invention, what I claim as new and desire to secure by Letters Patent is:

1. In an article positioning mechanism of the class described, the combination with means for moving articles in a definite path, of positively actuated article contacting means in movable relation to said path and operable by frictional contact with the surface of an article or imparting a partial rotative movement to said article.
2. In an article positioning mechanism of the class described, the combination with means for moving an article with a period of rest or dwell and in a definite path, of article contacting means in rotatable relation to said

- path and operable during the period of rest or dwell and by frictional contact with the surface of an article for imparting a partial rotative movement thereto.
5. 3. In an article positioning mechanism, the combination of means for moving articles in a definite path and with a period of rest or dwell, and positively actuated article contacting means operable by direct frictional contact with the surface of an article and during the period of rest or dwell in the feed movement of said article for imparting a partial rotative movement thereto.
4. In an article positioning mechanism, 15 the combination of means for moving articles in a definite path and with successive periods of rest or dwell, and a plurality of article contacting devices each positioned for direct frictional contact with the surface 20 of an article and said article contact devices being operable successively on said article during the periods of rest or dwell for imparting successive periods of rotative movement of said article.
25. 5. In an article positioning mechanism, the combination of means for moving articles in a definite path and with a period of rest or dwell, and article contacting means in rotatable relation to the article path and positioned for frictional wiping contact directly with the surface of said article during its period of rest or dwell for imparting rotative movement thereto.
6. In an article positioning mechanism, 35 the combination of means for moving an article in a definite path and with successive periods of rest or dwell, and a plurality of article contacting devices in rotatable relation to the article path, said article contacting devices being positively actuated and being positioned for frictional contact with the surface of an article during its successive periods of rest or dwell.
40. 7. In an article positioning mechanism, 45 the combination with means for moving an article in a definite path, of a rotatable brush positioned for frictional contact directly with the surface of an article and operable for imparting rotative movement to said article.
50. 8. In an article positioning mechanism, 55 the combination with means for moving an article in a definite path, of a plurality of rotary brush devices positioned for successive contact directly with the surface of an article and each operable by frictional contact therewith for imparting a rotative movement to the article.
60. 9. In an article positioning mechanism, 65 the combination with means for moving an article in a definite path, and with a period of rest or dwell, of a rotary brush positioned for frictional contact with the surface of the article at its period of rest or dwell, said brush being operable for imparting rotative movement bodily to said article.
10. In an article positioning mechanism, the combination with means for moving an article in a definite path, and with successive periods of rest or dwell, of a plurality of 70 rotary brushes positioned contiguous to said article path and adapted for frictional contact directly with the surface of an article at the successive periods of rest or dwell for imparting rotative movement thereto. 75
11. In an article positioning mechanism, the combination of means for moving in a definite path an article the surface of which is irregular by the presence of identification matter thereon, and article contacting means 80 positioned for frictional contact with such irregular surface of the article, said article-positioning means being positively actuated with respect to the article path for imparting a partial rotative movement to said article. 85
12. In an article positioning mechanism, the combination of means for moving in a definite path an article the surface of which is irregular by the presence of identification matter thereon, and article contacting means 90 in rotatable relation to the article path and positioned for frictional contact with such irregular surface of the article whereby the rotative movement of said article contacting means is communicated to said article. 95
13. In an article positioning mechanism, the combination of means for moving in a definite path and with a period of rest or dwell an article the surface of which is irregular by the presence of identification matter thereon, article contacting means positioned for frictional contact with such irregular surface of the article during the period of rest or dwell, and means for positively rotating said article-contacting means 100 whereby the article is rotated bodily by such frictional contact therewith of the article-positioning means.
14. In an article positioning mechanism, the combination with means for moving in a 110 definite path an article the surface of which is irregular by the presence of identification matter thereon, a rotary brush positioned adjacent the article path and adapted for rotative frictional contact with the irregular surface of the article, and means for positively rotating said brush whereby the article is rotated bodily by the frictional contact of said brush therewith.
15. In an article positioning mechanism, 120 the combination with means for moving in a definite path and with periods of rest or dwell an article the surface of which is irregular by the presence of identification matter thereon, and a plurality of rotary 125 brushes positioned adjacent the article path and adapted for contact with the irregular surface of the article during the periods of

- rest or dwell for imparting rotative movement to said article.
16. In an article positioning mechanism, a plurality of devices operable for moving 5 articles in a definite path and to successive positions by the contact of one article with another article, in combination with means positioned for rotative frictional contact with an article for imparting rotative movement to each article.
17. In an article positioning mechanism, a plurality of devices operable for moving articles to successive positions by the contact of a following article with a preceding article, 15 in combination with positively actuated means having wiping contact with an article for imparting rotative movement to each article.
18. In an article positioning mechanism, a 20 plurality of devices for moving articles in a definite path and by the impact of a following article with a preceding article, in combination with a rotatable brush positioned for frictional contact with an article 25 and operable for imparting a partial rotative movement thereto.
19. In an article positioning mechanism, a 30 plurality of devices for intermittently moving articles in a definite path and by the pressure of a following article with a preceding article, in combination with a plurality 35 of devices in rotatable relation to the article path and positioned for frictional contact with said articles to impart rotative movement thereto.
20. In an article positioning mechanism, means for moving an article in a definite path, an article rotative means at one side of said path, and means for shifting articles 40 out of the path and restoring them to said path, said shifting means being operable in presenting an article to said article rotative means.
21. In an article positioning mechanism, 45 means for moving articles in a definite path, a brush device positioned at one side of said article path and operable on an article for imparting rotative movement thereto, and means for presenting articles successively to said brush device, said presenting means being operable in shifting each article out of the article path and in restoring the article to said article path.
22. In an article positioning mechanism, 55 means for moving articles in a definite path, a brush device positioned at one side of said article path and operable on an article for imparting rotative movement thereto, and an article pusher operable for presenting articles successively to said brush device.
23. In an article positioning mechanism, a 60 rotary brush operable for imparting a partial rotative movement to an article, means for feeding articles successively to said rotary brush, a second rotary brush positioned 65 adjacent the path of movement of the articles, and means co-operating with the second rotary brush for presenting articles successively thereto.
24. In an article positioning mechanism, a 70 plurality of rotary brush devices operable successively upon an article for imparting a partial rotative movement thereto, in combination with means for arresting the movement of an article from one device to the 75 other device.
25. In an article positioning mechanism, a 80 plurality of rotary brush devices operable successively upon an article for imparting a partial rotative movement thereto, in combination with means for feeding articles from one brush device to the succeeding brush device, and means for precluding the feed of an article from one brush device to the succeeding brush device until the succeeding brush device shall have acted upon 85 an article presented thereto.
26. In an article positioning mechanism, a 90 plurality of brush devices operable successively upon an article for imparting rotative movement thereto, in combination with article feeding means, and an escapement member positioned in the path of the article feed and operable to preclude the movement of an article from one brush device to the 95 other brush device.
27. In an article positioning mechanism, a 100 plurality of brush devices operable successively upon an article for imparting rotative movement thereto, in combination with article feeding means, an escapement member positioned in the path of article feed, and means for automatically withdrawing 105 said escapement member from said path.
28. In an article positioning mechanism, a 110 rotary brush mechanism operable for imparting rotative movement to an article, in combination with an article pusher member operable to feed an article under spring pressure to said brush mechanism.
29. In an article positioning mechanism, a 115 rotary brush mechanism operable for imparting rotative movement to an article in combination with an article pusher member operable to feed an article under spring pressure to said brush mechanism, and cam controlled means for controlling the action of 120 said pusher member and for positively returning to an active position said pusher member.
30. In an article positioning mechanism, a 125 plurality of brush mechanisms each operable for imparting a partial rotative movement to an article, in combination with a plurality of article pushers each operable for moving an article under spring pressure to one of said brush mechanisms, and cam controlled mechanism for effecting the return in due order of said pusher members 130 to active positions.

31. The combination with a labeling mechanism, of article positioning means including a brush mechanism operable for imparting rotative movement to an article, and 5 a carrier for moving the articles so positioned into co-operative relation to said labeling mechanism.
32. The combination with labeling mechanism, of article positioning means including 10 an intermittent article feed and a brush mechanism operable for imparting a rotative movement to said article to present a label receiving surface on said article in facing relation to the labeling mechanism, 15 and an intermittent article carrier for moving the articles so positioned from said article positioning means to said labeling mechanism.
33. In a labeling machine, the combination 20 with label-applying means, of means for moving an article to said label-applying means with intervals of rest or dwell in the movement of said article, and positively actuated means having wiping contact with 25 said article prior to the presentation of the article to the label-applying means; said positively actuated means acting on said article for rotating the same during the period of its rest or dwell.
34. In a labeling machine, the combination 30 with label-applying means, of feeding means upon which is imposed an article adapted for unrestrained rotative movement, and positively-actuated means co-operable 35 with said article prior to its presentation to the label-applying means, said positively-
- actuated means having frictional contact with a roughened surface of said article and operating for rotating the article bodily to present a label-receiving surface in the required relation to the label-applying means. 40
35. In a labeling machine, the combination with label-affixing mechanism, and article-feed mechanism whereon an article is imposed for free rotation relatively to said 45 article-feed mechanism, of rotary mechanism operable by frictional contact directly with the surface of said article for imparting bodily rotative movement to said article whereby the position of said article is shifted 50 for presenting a definite label-receiving surface thereon to said label-affixing mechanism.
36. In a labeling machine, the combination 55 with label-affixing mechanism, and article-feed mechanism whereon an article rests by gravity for rotation freely with respect to said article-feed mechanism, of a plurality of rotative brush devices positioned relatively to said article-feed mechanism for direct contact with the surface of an article, said brush devices being operable during the transportation stage of the article for imparting bodily rotative movement to said article with respect to the article-feed mechanism whereby the article is presented to the label-affixing mechanism for a definite label-receiving surface of said article to receive the label. 60

In testimony whereof I have hereto signed 70
my name this 19 day of March, 1926.

CHAS. S. WEEKS.
